UNITED STATES PATENT OFFICE.

ALFRED F. BEAULIEU, OF CHICAGO, ILLINOIS.

MEASURING INSTRUMENT.

1,255,850.

Specification of Letters Patent. Patented Feb. 12, 1918.

Application filed September 16, 1915, Serial No. 51,057. Renewed December 20, 1917. Serial No. 203,151.

To all whom it may concern:

Be it known that I, ALFRED F. BEAULIEU, a citizen of the United States, residing at Chicago, in the county of Cook and State 5 of Illinois, have invented certain new and useful Improvements in Measuring Instruments, of which the following is a specification.

My invention relates to measuring instruments and more particularly to a combined bevel protractor square and divider.

The primary object of my invention resides in the provision of an instrument for use by draftsmen, carpenters, machinists 15 and mechanics in general embodying novel means for removably holding a square in various adjusted positions or angles through use of a protractor as well as means coöperating with these parts for adjustably holding dividers in a predetermined position thereby providing an efficient combination that can be easily and quickly adjusted and used in various capacities for assisting the 20 operator in maintaining and ascertaining 25 different angles and measurements.

Another object of my invention resides in the provision of a device of the character described that is simple in construction, efficient in operation and one that can be manufactured and placed upon the market at a minimum cost.

Other objects as well as the nature, characteristic features and scope of my invention will be more readily understood from 35 the following description taken in connection with the accompanying drawings and pointed out in the claims forming a part of this specification.

In the drawings:

40 Figure 1 is a top plan view of my invention;

Fig. 2 is a longitudinal central sectional view of my invention;

Fig. 3 is an end elevational view of the 45 invention.

Referring more particularly to the drawings in which similar reference numerals designate like or corresponding parts throughout the different views, I provide a 50 semicircular supporting protractor plate 1, the curved edge 2 of which is provided with radially arranged graduations 3. An elongated blade 4 is formed integral with and projects from intermediate the ends of the 55 curved edge, said blade being provided on both sides with graduations 5 and which

blade is arranged in position perpendicular to the straight edge 6 of the plate 1. The common center of the semicircular plate is provided with an opening 7 through which 60 passes from the under surface of the plate a bolt 8 which serves to pivotally connect a metallic square 9 thereto at the point of juncture of the arms of the square. This square has a long arm 10 of a configuration 65 similar to the blade 4, the short arm 11 thereof terminating adjacent the graduations 3 of the plate. A pointer 13 projects from intermediate the ends of the free edge of the short arm and facilitates ascertaining 70 the various desired angles through the medium of the long arm 10.

In order to maintain the long arm 10 in various adjusted angles, I have provided a bolt 13 which is slidably arranged in a semi-circular slot 14 in the plate 1, said slot being arranged in spaced circumferential relation with the curved edge 2. The free threaded end of the bolt extends through the short arm 11 adjacent the free end thereof and is adjustably engaged by a knurled nut 15 which coöperates with the head of the bolt arranged on the under surface of the plate 1, for removably maintaining the square in position.

Similarly formed divider legs are pivotally connected about the bolt 8 and removably maintained in adjusted positions through the medium of a knurled nut 17, the divider legs are of a width similar to the 90 width of the blade 5 and long arm 10, the rounded pointed ends 18 of the legs terminating in alinement with the blade 4 and long arm 10 as illustrated to advantage in the accompanying drawings. The legs 16 95 and the arms of the square 17 when swung about their pivot may be arranged so that both of their side edges lie in alinement with the straight edge 6 of the plate 1, this arrangement permitting of the device being 100 used as a T-square.

The operation of my invention is as follows:

In using the device as a protractor, the legs 16 may be swung to project away from the 105 straight edge, this permitting of the square bolt carried by the short arm freely sliding throughout the entire length of the slot 14 thereby permitting of various desired angles being obtained. It is of course understood that when the desired angle has been ascertained by tightening the knurled nut 110

15, the long arm 10 will be removably maintained in the desired position of angular adjustment. In providing a carpenter's square, the outer side edge of the long arm 5 is arranged in alinement with the straight edge 6 and the short arm is arranged in alinement with the blade 4, whereupon the nuts 15 and 17 are tightened. By swinging the divider legs so that one of their side 10 edges are arranged in alinement with the straight edge 6 and by tightening the nut 17 a T-square is provided. The divider legs are held adjusted in various positions through the medium of the nut 17, the 15 graduations 3 provided on the curved edge facilitating the adjustment thereof.

Although I have shown and described the preferred embodiment of my invention, I desire to be understood that I am not to be limited to the exact details shown; however, 20 I desire that great stress be laid upon the arrangement of the novel coöperation existing between the square, protractor plate, blade and divider legs for providing a carpenter's square and a T-square as well as the indicator coacting with the graduations for determining different angles.

From the above description taken in connection with the accompanying drawings, it 30 can easily be seen that I have provided a device that is simple in construction, containing but a few simple parts that can be cheaply manufactured and assembled and when assembled can be placed upon the market and sold at a minimum cost.

It will be understood that the above description and accompanying drawings comprehend only the preferred embodiment of my invention and that various minor 40 changes in detail of construction, proportion and arrangement of the parts may be made within the scope of the appended claims and without sacrificing any of the advantages of my invention.

Having thus fully described my invention, what I claim as new and desire to secure by Letters Patent, is:—

1. A measuring instrument comprising a graduated protractor plate, a graduated 50 blade extending therefrom, a square body on the plate, and means for removably holding the arms of the square in various positions of angular adjustment with respect to the plate and blade.

55 2. A measuring instrument comprising a protractor plate, a blade extending therefrom, a square, a pair of divider legs, and means for removably clamping the divider legs and the long arm of the square on the plate to provide a T-square.

60 3. A measuring instrument including a

protractor plate having a curved edge and having graduations adjacent the curved edge thereof, a blade projecting from the curved edge, a square associated therewith, one arm 65 of said square being shorter than the other, an indicator pointer formed on the free edge of the short arm for association with the graduations, and means for adjustably maintaining the long arm in angular adjust- 70 ment.

4. A measuring instrument including a semicircular protractor supporting plate having a curved edge and provided with graduations along its curved edge, said plate 75 being also provided with a semicircular slot arranged in spaced circumferential relation with the curved edge, a blade projecting from intermediate the ends of the curved edge and arranged perpendicular to the 80 straight edge, a square pivoted to the center of the plate and having one arm shorter than the other, the long arm of the square being of a configuration similar to the configuration of the blade, a pointer on the 85 free edge of the short arm for association with the graduations along the curved edge of the plate, a bolt slidably arranged in the slot and projecting through the short arm for guiding the movement of the square, a 90 nut on the bolt for removably maintaining the pointer in a predetermined position to consequently maintain the long arm at a predetermined angle, and the long arm of the square adapted to be arranged in alinement 95 with the straight edge of the plate, at times to provide a carpenter's square.

5. A measuring instrument including a protractor supporting plate having a curved edge and a straight edge, a blade 100 projecting from intermediate the ends of the curved edge and arranged perpendicular to the straight edge, a square pivotally associated with the plate, one arm of said square being shorter than the other, an indicator 105 on the free edge of the short arm for association with the curved edge of the protractor plate, means for adjustably clamping the short arm in various positions to consequently maintain the long arm of a 110 square at a desired angle, divider legs pivotally associated with the plate and square, and means for clamping the divider legs and the long arm of the square to provide a T-square.

115 In testimony whereof I affix my signature in presence of two witnesses.

ALFRED F. BEAULIEU.
